(57) **CLAIM**

The ornamental design for a lamp as shown and described.

DESCRIPTION

FIG. 1 shows a top perspective view of the lamp.

FIG. 2 shows a left side view thereof.

FIG. 3 shows a front view thereof.

FIG. 4 shows a right side view thereof.

FIG. 5 shows top view thereof.

FIG. 6 shows a bottom view thereof; and,

FIG. 7 shows a back view thereof.

The name 'FERMOB' appearing in some drawings and forming part of the claimed design is a registered trademark owned by the applicant FERMOB.

The broken lines shown in the figures depict portions of the lamp that form no part of the claimed design.

1 Claim, 7 Drawing Sheets
